UNITED STATES PATENT OFFICE.

EDWIN SAMUEL RAUWORTH, OF DE KALB, ILLINOIS, ASSIGNOR TO APOLLO PIANO COMPANY, OF DE KALB, ILLINOIS, A CORPORATION OF ILLINOIS.

APPARATUS FOR LEVELING PIANO KEYS.

Application filed July 28, 1923. Serial No. 654,433.

This invention relates to a method and apparatus for aligning or leveling the keys of a piano when assembled in the case, but preferably before installation of the piano action. It consists of certain features and devices in combination as herein shown and described and as indicated by the claims.

In the drawings:

Figure 1 is a partial front elevation of a piano case with the keys mounted therein and with devices embodying this invention positioned for use.

Figure 2 is a detail section taken as indicated at line 2—2 on Figure 1.

Figure 3 is a transverse section taken as indicated at line 3—3 on Figure 1.

Each of the keys, A, is retained at its fulcrum by an upstanding post or pin, B, provided with a felt washer or pad, 1, and in some instances with one or more paper shims, 2. It is desirable, for the sake of appearance and also to avoid interference with the technique of the musician, that in their normal position the keys should stand in alignment but this is not always the case after the initial assembly. For correcting the alignment the number or thickness of the shims, 2, applied to the fulcrum pin, B, must be varied and to permit this it is necessary to raise the key a considerable distance to the dotted line position indicated in Figure 3 at A¹. This is not possible if the regular piano action is already in position; therefore for the purposes of the leveling operation I provide a dummy action designed to apply to the inner end of each key substantially the same weight or pressure as it would experience if the regular action were in place.

The dummy action consists of supporting frame structure, 3, having lugs, 4, to which there are pivoted at 5 a plurality of weighted arms, 6, which may be made of laminated wood bored to carry a number of lead weights, 7, as indicated in Figures 2 and 3. The weighted portion of each of the arms, 6 carries a contact button, 8, resting upon one of the keys so that in the normal range of movement of the key it experiences at this point substantially the pressure which the regular action would place upon it. The arms, 6, however, are free to swing individually about their fulcrums at, 5, through a wide range so as to permit raising the keys sufficiently to

remove or apply the shim washers, 2, at the fulcrum pins, B. At their forward edges the arms, 6, are formed with fingers pieces, 6^a, to facilitate lifting them individually in withdrawing or replacing any single key to which may require special fitting. The dummy action is firmly held in place during the testing and adjusting of the keys by the application of clamps, 9, which at one end engage lugs, 3^a, on the brackets, 3, and at their opposite ends are fitted with clamp screws, 9^a, to engage the forward edges of the key frame.

In conjunction with the dummy action I employ a measuring instrument in the nature of a depth gauge comprising end brackets or supports, 10, which rest upon the bed or frame, C, of the piano case and support a substantially rigid straight steel bar, 11, upon which there is slidably mounted a carriage, 12. The depth gauge proper includes a graduated dial, 13, having a needle, 14, which is actuated to traverse the dial by up or down movements of a plunger, 15, having a contact button, 16, at its lower end positioned to engage the top surface of the piano key. The case, 17, of the gauge is carried by a bracket, 18, secured to the lower end of the rod, 19, whose upper end is threaded and provided with an adjusting nut, 20, by which the gauge may be raised or lowered with respect to the carriage, 12, for setting its initial position with respect to the bed, C, of the piano case. The end brackets, 10, are furnished with leveling screws, 21, so that the bar, 11, may be firmly supported on the bed, C.

To use the apparatus a certain dial reading is chosen to represent the normal or desired position of the keys in their inoperative position. Beginning at one end of the keyboard the contact button, 16, of the gauge is then applied to the first key and the reading on the dial, 13, is noted. The amount of variance of the reading from the normal value will indicate to the workman substantially how much thickness should be added to, or subtracted from, the supporting pad, 1, and shims, 2, at the fulcrum pin, B. He then selects a shim or shims of the proper thickness from an assortment and places such shim or shims on the ledge of the key bed, C, directly in front of the tested key. After all the white keys have been tested, it is but the work of a few seconds

to insert the selected shims at the fulcrum pins, B, lifting the keys to the position, A¹, for this purpose.

Then the process is applied to the black keys.

By providing shims of several thicknesses and if necessary furnishing special thin or thick pads, 1, it becomes a simple matter for the workman to determine from the first 10 gauge reading just what shims he should add to bring the key to a normal level. If the keys are all assembled without any shims but merely with the pads, 1, in place, a normal level may be chosen which will require at least one shim washer, 2, in practically every case.

Another application of the apparatus is for securing a uniform depression for the keys; this dimension is determined by the 20 depth of pads and shims, 1^a and 2^a, respectively, which are applied to the post or pin, D, located under the forward end of each key and projecting into a recess, E, therein when the key is depressed. A definite gauge reading is chosen to correspond to the desired position of the key at full depression and by depressing each key and applying the gauge the workman is enabled to judge just what thickness of shims, 2^a, to add to the pad, 1^a, for arresting the key movement at this predetermined limit. Preferably the shims are applied under the pads so that the felt pad may be left uppermost to keep the key action as quiet as possible. As in leveling the keys at normal position two settings of the gauge will be required in adjusting the depression,—one setting for the white keys and a separate setting for adjusting the black keys.

40 I claim:—

1. A key leveling apparatus comprising a guide rail with standards for supporting it over the keys of a piano, a depth gauge slidably mounted on said rail and having a vertically movable member which may be lowered at will into contact with the keys, one at a time, and including an indicator operable by the movable member for showing the position of the latter with reference 45 to a predetermined normal.

2. In the apparatus defined by claim 1, a carriage supporting said gauge on said rail and provided with means for raising and lowering the gauge bodily on the guide 50 rail.

3. In combination with a guide rail provided with standards for supporting it over the keys of a piano, and a gauge device slidably mounted on said rail and having a member adapted to depend for engagement 60 with the piano keys, one at a time, a dummy action comprising a series of arms and a support upon which they are fulcrumed in position to rest upon the respective keys of the piano, to impose a load thereon in lieu 65 of the weight of the piano action, said arms being mounted to swing freely upward to permit raising the keys sufficiently to clear their fulcrum pins.

4. In the combination defined in claim 3, 70 said arms being individually pivoted to swing about their fulcrums independently of each other, and means extending from each arm to serve as a handle for so swinging it. 75

5. In the combination defined in claim 3, 80 said arms being individually pivoted to swing about their fulcrums independently of each other, and a forwardly exposed finger piece on each arm to facilitate lifting the arm. 85

6. In the apparatus defined in claim 1, a carriage on the guide rail and a casing for the depth gauge vertically movable on said carriage with a stop for limiting the downward movement of the casing; the said member which contacts with the keys being vertically movable with respect to the casing independently of the movement of the latter on the carriage whereby said member may 90 be arrested by its contact with the keys independently of the stop which limits the lowering of the casing.

7. In the apparatus defined in claim 1, a carriage on the guide rail and a casing for 95 the depth gauge, vertically movable on said carriage, with a stop for limiting the downward movement of the casing; the said member which contacts with the keys being vertically movable with respect to the casing, 100 independently of the movement of the latter on the carriage, whereby said member may be arrested by its contact with the keys independently of the stop which limits the lowering of the casing; and means for adjusting said stop vertically for setting the predetermined normal. 105

In testimony whereof, I have hereunto set my hand at De Kalb, Illinois.

EDWIN SAMUEL RAUWORTH.
